UNITED STATES PATENT OFFICE.

EDWARD E. KILBOURN, OF NEW BRUNSWICK, NEW JERSEY, ASSIGNOR TO
THE KILBOURN KNITTING MACHINE COMPANY.

MANUFACTURE OF SEAMLESS HOSEYER.

No. 850,940.

Specification of Letters Patent.

Patented April 23, 1907.

Application filed January 30, 1903. Serial No. 141,129.

To all whom it may concern:

Be it known that I, EDWARD E. KILBOURN, a citizen of the United States, residing at New Brunswick, in the county of Middlesex and State of New Jersey, have invented certain new and useful Improvements in the Manufacture of Seamless Hosiery; and I do hereby declare the following to be a full, clear, and exact description of the invention, such as will enable others skilled in the art to which it appertains to make and use the same.

My present invention relates to the art of knitting seamless hosiery, and has for its object the making of a seamless stocking embracing certain new and ornamental effects.

It consists in a stocking of the class described provided with drop-stitch ornamentation applied in a novel manner and producing novel results.

In the drawings I have shown a stocking embodying my present invention, and my said invention is disclosed in the following description and claims.

Figure 1 is a view of a stocking embodying my said improvements. Fig. 2 is an enlarged view of a portion of the stocking at the point of casting off of stitches. Fig. 3 is a view of a half-hose embodying my invention.

In the drawings, A indicates the leg, and B the foot, of the stocking. The stocking is made with a plain welt or hem a' at the top of the leg. Immediately below the hem in this instance certain of the needles are caused to cease knitting, making open-work spaces c c c, the thread in such spaces extending directly across a space as wide as that occupied by a single stitch of plain knitting or wider. At the point a' all of the needles are again operated to make plain knitting, and at the point a² the same needles are again caused to cease knitting and the drop-stitch open-work is again produced.

The open-work, as shown, extends around the leg of the stocking on the back as well as on the front. The needles which cease knitting to form the open-work at the back of the leg are thrown into operation for plain knitting at the point a³ above the heel of the stocking, and the needles which cease knitting to form the open-work upon the front of the leg of the stocking are caused to resume plain knitting at some point, as b, above the

toe. The stocking therefore has the open-work all around the leg and has plain-knitted portions above the drop-stitch open-work and plain knitting between the open-work and the toe. The stocking has also the heel, bottom of the foot, and the toe knitted in plain stitches.

When the needles are thrown out of or changed in operation so as to produce the open-work, they drop or cast off their stitches or loops. In case this is done immediately below the hem or welt the hem or welt will prevent the dropped stitches from raveling or opening out to the plain knitting above. In case, however, these needles are so changed at a point a distance below the welt or hem—for example, at the point a² in the drawings—the loops or stitches so cast off must be secured in some way. They may be secured by crocheting, by a line of stitching, or by causing a number of needles closely adjacent to the drop-stitch needles to knit one or more tuck-strokes before the drop-stitch needles cast off, as shown at c', Fig. 2. This is the preferred manner of securing such loop or stitches at such places, and this dropping and securing of the stitches may take place at any point of the stocking desired.

It will be evident that the pattern illustrated may be very considerably varied without departing from the spirit of my invention. For example, several bands of plain knitting may be formed around the leg of the stocking, or the plain knitting may be continuous from the top down to a desired point and the remainder of the leg of the stocking knit with the open-work, or the machine may be operated to form bands of open-work at intervals down the leg of the stocking.

In Fig. 2 I have shown the tuck-strokes c' as made on each side of the dropped stitches and for two courses preceding the dropping of such stitches. This is the mode I prefer; but the tuck-strokes may be in a larger number of courses or may be in a single course only. While I prefer to have the tuck-strokes on each side of the dropped stitches, it will not be necessary in all cases, as a tuck-stitch at one side will with some kinds of thread or yarn be found sufficient.

In making half-hose I prefer to knit plain knitting for a short distance below the ribbed top and thereafter begin the drop-stitch work.

In Fig. 3 the dotted line *d* indicates the line of joining the ribbed top to the top of the leg of the stocking, and *d'* the point of beginning the drop-stitch work. *d²* indicates the point at which the drop-stitch work ceases on the back of the stocking. The point at which the drop-stitch work is discontinued on the top of the foot of the stocking would be about the same as that on the full hose shown.

I may accomplish the work desired by having separate cam-grooves, dividing the needles between the grooves, and then controlling the cams of each class of needles to produce the work desired, or I may accomplish this by using needles having nibs of different lengths and then controlling the operating-cams. In each mode of procedure the work will be controlled by pattern mechanism.

What I claim, and desire to secure by Letters Patent, is—

1. A machine-knit seamless stocking having drop-stitch open-work upon the leg of the stocking, solid plain knitting preceding such drop-stitch open-work and tuck-stitches at the beginning of the open-work, substantially as described.

2. A machine-knit seamless stocking having drop-stitch open-work around the leg of the stocking with solid plain knitting above the drop-stitch work and tuck-stitches secur-

ing the drop-stitch work, substantially as described.

3. A machine-knit seamless stocking having drop-stitch open-work around the leg of the stocking, at the back as well as the front of the leg of the stocking, with solid plain knitting above the drop-stitch work, and tuck-stitches securing the drop-stitch work, the thread forming the leg being continuous with the thread forming the main portion of the foot of the stocking, substantially as described.

4. A machine-knit seamless stocking, having drop-stitch open-work upon the leg of the stocking, with solid plain knitting above said open-work, the dropped stitches preceding the open-work being secured, substantially as described.

5. A machine-knit seamless stocking, having drop-stitch open-work around the leg of the stocking at the back as well as the front of the stocking, with solid plain knitting preceding the drop-stitch work, the dropped stitches preceding the open-work being secured, substantially as described.

In testimony whereof I affix my signature in the presence of two witnesses.

E. E. KILBOURN.
